[57] CLAIM

The ornamental design for a storage cabinet for vehicles, as shown and described.

DESCRIPTION

FIG. 1 is a top front perspective view of a storage cabinet for vehicles, showing my new design;
FIG. 2 is a front elevational view thereof;
FIG. 3 is a top plan view thereof;
FIG. 4 is a right side elevational view thereof, the left side being a mirror image thereof; and
FIG. 5 is a rear elevational view thereof.

Fig. 4
